US0D1040949S

(12) United States Design Patent (10) Patent No.: US D1,040,949 S
(45) Date of Patent: * Sep. 3, 2024

(54) EXERCISE MACHINE COMPONENT

5,556,369 A 9/1996 Roberts
6,110,081 A 8/2000 Barrett
6,296,594 B1 10/2001 Simonson

(71) Applicant: TONAL SYSTEMS, INC., San Francisco, CA (US)

(Continued)

(72) Inventors: Robin Barata, San Francisco, CA (US); Nina Samarguliani, Oakland, CA (US); Daniel K. Harden, Carmel, CA (US); Yale F. Shaw, San Francisco, CA (US); Ariel D. Turgel, San Francisco, CA (US)

FOREIGN PATENT DOCUMENTS

EM 009066723-0001 * 7/2022
EM 009066723-0002 * 7/2022

(Continued)

(73) Assignee: TONAL SYSTEMS, INC., San Francisco, CA (US)

() Term: 15 Years

(21) Appl. No.: 29/820,608

(22) Filed: Dec. 22, 2021

(51) LOC (14) Cl. 21-02

(52) U.S. Cl.
USPC D21/686; D21/662; D21/696; D14/126;
D14/374

(58) Field of Classification Search

USPC D21/662, 686, 694, 696; D14/302, 421,
D14/444, 900, 126, 133, 371, 374
CPC A63B 2071/0658; A63B 21/169; A63B
21/4035; A63B 2210/06; A63B 2220/805;
A63B 2220/806; A63B 24/0062; A63B
71/0622

See application file for complete search history.

(56) References Cited

U.S. PATENT DOCUMENTS

195,116 A	9/1877	Foster
1,372,026 A	3/1921	William
3,117,781 A	1/1964	Vargo
5,029,850 A	7/1991	van Straaten
5,362,296 A	11/1994	Wang
D353,419 S	12/1994	Sprague

Home Gym Supply, NordicTrack Vault, published on Sep. 11, 2022 [online]. Retrieved from internet (Date: Sep. 15, 2023), <https://homegymsupply.co.uk/products/nordictrack-vault> (Year: 2022).*

(Continued)

Primary Examiner — Katherine A Holbrow

Assistant Examiner — Riya Salil Kamat

(74) Attorney, Agent, or Firm — Barnes & Thornburg
LLP

(57) CLAIM

The ornamental design for an exercise machine component, as shown and described.

DESCRIPTION

FIG. 1 is a front perspective view of an exercise machine component according to an embodiment of our new design; FIG. 2 is a front elevation view of the exercise machine component of FIG. 1;

FIG. 3 is a right side elevation view of the exercise machine component of FIG. 1, the left side being a minor image thereof; and,

FIG. 4 is a bottom plan view of the exercise machine component of FIG. 1.

The broken lines shown in the drawings are for purposes of illustrating portions of the exercise machine component that form no part of the claimed design.

1 Claim, 4 Drawing Sheets

US D1,040,949 S

Page 2

(56)	References Cited
U.S. PATENT DOCUMENTS
D482,748 S	11/2003 Flynt	2005/0075223 A1	4/2005	Wu
6,659,922 B1	12/2003 Yu	2005/0137066 A1	6/2005	Wu
D502,515 S	3/2005 Carter	2006/0223683 A1	10/2006	Orona
7,115,078 B1	10/2006 Kalember	2007/0015644 A1	1/2007	Aucamp
7,172,538 B2	2/2007 Keiser	2007/0042881 A1	2/2007	Wu
D572,776 S	7/2008 Wells	2007/0093369 A1	4/2007	Bocchicchio
D586,410 S	2/2009 Citterio	2007/0207904 A1	9/2007	Wu
7,601,105 B1	10/2009 Gipson	2008/0300116 A1	12/2008	Eder
7,608,024 B2	10/2009 Sechrest	2009/0176634 A1	7/2009	Wu
D605,712 S	12/2009 Bizzell	2010/0255966 A1	10/2010	Aucamp
D606,134 S	12/2009 Bizzell	2013/0090216 A1	4/2013	Jackson
D612,437 S	3/2010 Fenster	2013/0157816 A1	6/2013	Lysczarz
8,096,926 B1	1/2012 Batca	2015/0031512 A1	1/2015	Schleiden, II
D679,764 S	4/2013 Alessandri	2015/0182773 A1	7/2015	Olson
8,500,607 B2	8/2013 Vittone	2017/0150786 A1	6/2017	Ness
8,506,459 B2	8/2013 Cassidy	2017/0172832 A1	6/2017	Rosario, Jr.
8,550,964 B2	10/2013 Ish, III	2017/0232302 A1	8/2017	Dedvukaj
D692,971 S	11/2013 Alessandri	2017/0246507 A1	8/2017	Kennington
D692,972 S	11/2013 Alessandri	2017/0319941 A1*	11/2017	Smith	A63B 21/06
D708,274 S	7/2014 Eder	2017/0333742 A1	11/2017	Reese
9,162,102 B1	10/2015 Eder	2018/0021616 A1	1/2018	Orady
D742,461 S	11/2015 Baldwin	2018/0243600 A1	8/2018	Kennington
D746,925 S *	1/2016 Firth	D21/686	2019/0099632 A1	4/2019	Orady
9,656,116 B2	5/2017 Giannelli	2019/0099633 A1	4/2019	Orady
9,744,400 B2	8/2017 Cole	2019/0099637 A1	4/2019	Valente
D807,445 S	1/2018 Gettle	2019/0099652 A1	4/2019	Orady
D820,825 S *	6/2018 Foster	D14/307	2019/0299042 A1	10/2019	Slayton
D842,398 S	3/2019 Zhu	2019/0308057 A1	10/2019	Chen
D847,107 S *	4/2019 Cleveland	D14/126	2020/0047027 A1	2/2020	Ward
10,500,442 B2	12/2019 Hong	2020/0047031 A1*	2/2020	Orady	A63B 24/0062
D891,541 S	7/2020 Lin	2020/0086197 A1	3/2020	Kim
D895,030 S	9/2020 Jaquish	2021/0236874 A1*	8/2021	Ward	A63B 24/0087
D895,031 S	9/2020 Jaquish	2021/0387038 A1	12/2021	Premachandra
D895,032 S	9/2020 Jaquish	2022/0118301 A1	4/2022	Valente
D895,033 S	9/2020 Jaquish	2022/0288447 A1	9/2022	Spurgin
D895,739 S	9/2020 Jaquish	FOREIGN PATENT DOCUMENTS
D905,179 S *	12/2020 Kennington	GB 6214784	*	6/2022
D912,168 S *	3/2021 Orady	GB 6215034	*	6/2022
D921,132 S *	6/2021 Orady	GB 6215093	*	6/2022
D929,355 S *	8/2021 Diao	GB 6220437	*	6/2022
11,097,148 B2 *	8/2021 Kennington	A63B 21/169	OTHER PUBLICATIONS
D933,654 S *	10/2021 Chung	D14/371	Ana Suarez, Tempo Studio review, published on Dec. 28, 2022 [online]. Retrieved from internet (Date: Sep. 15, 2023), https://www.timesunion.com/shopping/article/Tempo-Studio-review-15802859.php (Year: 2022).*
D934,354 S *	10/2021 Kim	D21/673	Tonal, Entire Gym on Your Wall, published on Oct. 9, 2018 [online]. Retrieved from internet (Date: Sep. 15, 2023), http://web.archive.org/web/20181009063329/https://www.tonal.com/equipment/ (Year: 2018).*
D937,367 S *	11/2021 Behar	D21/673	Project Health, Top 6 Best Smart Gyms, published on Jun. 5, 2021 [online]. Retrieved from internet (Date: Sep. 19, 2023), https://www.youtube.com/watch?v=7ExtTIUIWeg (Year: 2021).*
D937,368 S *	11/2021 Behar	D21/673	Cnet, “Tonal Review”, Published Date: Mar. 24, 2022, accessed on the Internet at: https://www.cnet.com/health/fitness/tonal-review/ (Year: 2022).
D946,673 S	3/2022 Behar	D946,674 S	3/2022 Behar	Tonal, “Tonal”, Sep. 16, 2020. https://www.tonal.com/equipment/ . Shown on p. 1. (Year: 2020).
D947,964 S *	4/2022 Kim	D21/673	D949,262 S	4/2022 Horita	Youtube, “Meet Tonal”, Aug. 16, 2018. https://www.youtube.com/watch?v=j1RdHmefjml . Shown at the 1:55 minute mark. (Year: 2018).
D952,775 S *	5/2022 Kim	D21/686	D953,754 S *	6/2022 Asikainen	D957,551 S *	7/2022 Kim	D959,421 S *	8/2022 van de Ven	D962,220 S *	8/2022 Jung	D962,655 S *	9/2022 Li	D975,804 S *	1/2023 Orady	D987,747 S *	5/2023 Fan	D991,927 S *	7/2023 Jung	D994,657 S *	8/2023 Obrecht	D996,831 S *	8/2023 Cai	D997,572 S *	9/2023 Luo	D905,179 S *	10/2021 Chung	D933,654 S *	10/2021 Kim	D934,354 S *	10/2021 Kim	D937,367 S *	11/2021 Behar	D937,368 S *	11/2021 Behar	D946,673 S	3/2022 Behar	D947,964 S *	4/2022 Kim	D952,775 S *	5/2022 Kim	D953,754 S *	6/2022 Asikainen	D957,551 S *	7/2022 Kim	D959,421 S *	8/2022 van de Ven	D962,220 S *	8/2022 Jung	D962,655 S *	9/2022 Li	D975,804 S *	1/2023 Orady	D987,747 S *	5/2023 Fan	D991,927 S *	7/2023 Jung	D994,657 S *	8/2023 Obrecht	D996,831 S *	8/2023 Cai	D997,572 S *	9/2023 Luo	D905,179 S *	10/2021 Chung	D933,654 S *	10/2021 Kim	D934,354 S *	10/2021 Kim	D937,367 S *	11/2021 Behar	D937,368 S *	11/2021 Behar	D946,673 S	3/2022 Behar	D947,964 S *	4/2022 Kim	D952,775 S *	5/2022 Kim	D953,754 S *	6/2022 Asikainen	D957,551 S *	7/2022 Kim	D959,421 S *	8/2022 van de Ven	D962,220 S *	8/2022 Jung	D962,655 S *	9/2022 Li	D975,804 S *	1/2023 Orady	D987,747 S *	5/2023 Fan	D991,927 S *	7/2023 Jung	D994,657 S *	8/2023 Obrecht	D996,831 S *	8/2023 Cai	D997,572 S *	9/2023 Luo	D905,179 S *	10/2021 Chung	D933,654 S *	10/2021 Kim	D934,354 S *	10/2021 Kim	D937,367 S *	11/2021 Behar	D937,368 S *	11/2021 Behar	D946,673 S	3/2022 Behar	D947,964 S *	4/2022 Kim	D952,775 S *	5/2022 Kim	D953,754 S *	6/2022 Asikainen	D957,551 S *	7/2022 Kim	D959,421 S *	8/2022 van de Ven	D962,220 S *	8/2022 Jung	D962,655 S *	9/2022 Li	D975,804 S *	1/2023 Orady	D987,747 S *	5/2023 Fan	D991,927 S *	7/2023 Jung	D994,657 S *	8/2023 Obrecht	D996,831 S *	8/2023 Cai	D997,572 S *	9/2023 Luo	D905,179 S *	10/2021 Chung	D933,654 S *	10/2021 Kim	D934,354 S *	10/2021 Kim	D937,367 S *	11/2021 Behar	D937,368 S *	11/2021 Behar	D946,673 S	3/2022 Behar	D947,964 S *	4/2022 Kim	D952,775 S *	5/2022 Kim	D953,754 S *	6/2022 Asikainen	D957,551 S *	7/2022 Kim	D959,421 S *	8/2022 van de Ven	D962,220 S *	8/2022 Jung	D962,655 S *	9/2022 Li	D975,804 S *	1/2023 Orady	D987,747 S *	5/2023 Fan	D991,927 S *	7/2023 Jung	D994,657 S *	8/2023 Obrecht	D996,831 S *	8/2023 Cai	D997,572 S *	9/2023 Luo	D905,179 S *	10/2021 Chung	D933,654 S *	10/2021 Kim	D934,354 S *	10/2021 Kim	D937,367 S *	11/2021 Behar	D937,368 S *	11/2021 Behar	D946,673 S	3/2022 Behar	D947,964 S *	4/2022 Kim	D952,775 S *	5/2022 Kim	D953,754 S *	6/2022 Asikainen	D957,551 S *	7/2022 Kim	D959,421 S *	8/2022 van de Ven	D962,220 S *	8/2022 Jung	D962,655 S *	9/2022 Li	D975,804 S *	1/2023 Orady	D987,747 S *	5/2023 Fan	D991,927 S *	7/2023 Jung	D994,657 S *	8/2023 Obrecht	D996,831 S *	8/2023 Cai	D997,572 S *	9/2023 Luo	D905,179 S *	10/2021 Chung	D933,654 S *	10/2021 Kim	D934,354 S *	10/2021 Kim	D937,367 S *	11/2021 Behar	D937,368 S *	11/2021 Behar	D946,673 S	3/2022 Behar	D947,964 S *	4/2022 Kim	D952,775 S *	5/2022 Kim	D953,754 S *	6/2022 Asikainen	D957,551 S *	7/2022 Kim	D959,421 S *	8/2022 van de Ven	D962,220 S *	8/2022 Jung	D962,655 S *	9/2022 Li	D975,804 S *	1/2023 Orady	D987,747 S *	5/2023 Fan	D991,927 S *	7/2023 Jung	D994,657 S *	8/2023 Obrecht	D996,831 S *	8/2023 Cai	D997,572 S *	9/2023 Luo	D905,179 S *	10/2021 Chung	D933,654 S *	10/2021 Kim	D934,354 S *	10/2021 Kim	D937,367 S *	11/2021 Behar	D937,368 S *	11/2021 Behar	D946,673 S	3/2022 Behar	D947,964 S *	4/2022 Kim	D952,775 S *	5/2022 Kim	D953,754 S *	6/2022 Asikainen	D957,551 S *	7/2022 Kim	D959,421 S *	8/2022 van de Ven	D962,220 S *	8/2022 Jung	D962,655 S *	9/2022 Li	D975,804 S *	1/2023 Orady	D987,747 S *	5/2023 Fan	D991,927 S *	7/2023 Jung	D994,657 S *	8/2023 Obrecht	D996,831 S *	8/2023 Cai	D997,572 S *	9/2023 Luo	D905,179 S *	10/2021 Chung	D933,654 S *	10/2021 Kim	D934,354 S *	10/2021 Kim	D937,367 S *	11/2021 Behar	D937,368 S *	11/2021 Behar	D946,673 S	3/2022 Behar	D947,964 S *	4/2022 Kim	D952,775 S *	5/2022 Kim	D953,754 S *	6/2022 Asikainen	D957,551 S *	7/2022 Kim	D959,421 S *	8/2022 van de Ven	D962,220 S *	8/2022 Jung	D962,655 S *	9/2022 Li	D975,804 S *	1/2023 Orady	D987,747 S *	5/2023 Fan	D991,927 S *	7/2023 Jung	D994,657 S *	8/2023 Obrecht	D996,831 S *	8/2023 Cai	D997,572 S *	9/2023 Luo	D905,179 S *	10/2021 Chung	D933,654 S *	10/2021 Kim	D934,354 S *	10/2021 Kim	D937,367 S *	11/2021 Behar	D937,368 S *	11/2021 Behar	D946,673 S	3/2022 Behar	D947,964 S *	4/2022 Kim	D952,775 S *	5/2022 Kim	D953,754 S *	6/2022 Asikainen	D957,551 S *	7/2022 Kim	D959,421 S *	8/2022 van de Ven	D962,220 S *	8/2022 Jung	D962,655 S *	9/2022 Li	D975,804 S *	1/2023 Orady	D987,747 S *	5/2023 Fan	D991,927 S *	7/2023 Jung	D994,657 S *	8/2023 Obrecht	D996,831 S *	8/2023 Cai	D997,572 S *	9/2023 Luo	D905,179 S *	10/2021 Chung	D933,654 S *	10/2021 Kim	D934,354 S *	10/2021 Kim	D937,367 S *	11/2021 Behar	D937,368 S *	11/2021 Behar	D946,673 S	3/2022 Behar	D947,964 S *	4/2022 Kim	D952,775 S *	5/2022 Kim	D953,754 S *	6/2022 Asikainen	D957,551 S *	7/2022 Kim	D959,421 S *	8/2022 van de Ven	D962,220 S *	8/2022 Jung	D962,655 S *	9/2022 Li	D975,804 S *	1/2023 Orady	D987,747 S *	5/2023 Fan	D991,927 S *	7/2023 Jung	D994,657 S *	8/2023 Obrecht	D996,831 S *	8/2023 Cai	D997,572 S *	9/2023 Luo	D905,179 S *	10/2021 Chung	D933,654 S *	10/2021 Kim	D934,354 S *	10/2021 Kim	D937,367 S *	11/2021 Behar	D937,368 S *	11/2021 Behar	D946,673 S	3/2022 Behar	D947,964 S *	4/2022 Kim	D952,775 S *	5/2022 Kim	D953,754 S *	6/2022 Asikainen	D957,551 S *	7/2022 Kim	D959,421 S *	8/2022 van de Ven	D962,220 S *	8/2022 Jung	D962,655 S *	9/2022 Li	D975,804 S *	1/2023 Orady	D987,747 S *	5/2023 Fan	D991,927 S *	7/2023 Jung	D994,657 S *	8/2023 Obrecht	D996,831 S *	8/2023 Cai	D997,572 S *	9/2023 Luo	D905,179 S *	10/2021 Chung	D933,654 S *	10/2021 Kim	D934,354 S *	10/2021 Kim	D937,367 S *	11/2021 Behar	D937,368 S *	11/2021 Behar	D946,673 S	3/2022 Behar	D947,964 S *	4/2022 Kim	D952,775 S *	5/2022 Kim	D953,754 S *	6/2022 Asikainen	D957,551 S *	7/2022 Kim	D959,421 S *	8/2022 van de Ven	D962,220 S *	8/2022 Jung	D962,655 S *	9/2022 Li	D975,804 S *	1/2023 Orady	D987,747 S *	5/2023 Fan	D991,927 S *	7/2023 Jung	D994,657 S *	8/2023 Obrecht	D996,831 S *	8/2023 Cai	D997,572 S *	9/2023 Luo	D905,179 S *	10/2021 Chung	D933,654 S *	10/2021 Kim	D934,354 S *	10/2021 Kim .....</td

FIG. 1

FIG. 2

FIG. 3

FIG. 4